GOLF BALL POCKET

William T. Previdi, Allendale, N. J.

Application January 24, 1947, Serial No. 724,072

4 Claims. (Cl. 2—253)

1

This invention relates to new and useful improvements in articles of wear for golfers, and more particularly provides a main support and an inner and outer pocket combination on the support for carrying one or more golf balls according to an arrangement such that the inner pocket may be suspended within and secured inside the outer pocket when the latter is closed as by a slide fastener or so-called "zipper," or the inner pocket with its contained golf balls may be moved relative to its suspension in the outer pocket so as to hang outside the outer pocket after opening the closing means for the latter.

Thus, according to the invention, the inner pocket and its contents are protectively stored within the outer pocket with the latter closed, except at such times as the golf balls should be made completely accessible; yet, during a golf game and at a time when a new golf ball is desired to be put into play, the outer pocket may be opened and the inner pocket together with its contained golf balls may be lifted up and transferred for suspension outside the outer pocket, and so as then still to protectively house the golf balls but to place them at a location for quick removal from the pocket combination.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of the rear upper body of a golfer, showing an embodiment of the invention carried at the back of a jacket or the like worn by the golfer.

Fig. 2 is a front perspective view of a separate belt to be worn individually as such, and for carrying the inner and outer pocket combination of the invention; the rear of the outer pocket only being here shown.

Fig. 3 is a front elevation of the new device of the invention as carried either by a jacket, sweater, sweat shirt or the like, as indicated in Fig. 1, or as carried by a separate belt as shown in Fig. 2; the inner pocket here being shown as suspended at the outside of the outer pocket.

Fig. 4 is an enlarged perspective view, partially broken away and partially in section, of the device of the invention.

In Fig. 1, the new pocket combination, which throughout the views is generally marked 10, is

2

shown as carried by a belt-form or other addition 11 to the jacket 12; such addition being, for example, stitched to the jacket as indicated at 14, although as will be understood, the new pocket combination 10 may be secured in any suitable way directly to the jacket 12.

In Fig. 2, the pocket combination 10 is similarly suitably secured, as by the stitching 15, to an independent belt 16 having at its front ends cooperative snap fastener elements 17 and 18 for closing the belt so that it may be worn over the hips.

In all the views, a pocket combination 10 is shown as including a conventional outer pocket 15 unit comprising a front wall of textile material and a rear wall provided by a textile addition suitably stitched in place on the material constituting said front wall. Thus, in Fig. 1, the front wall of the outer pocket would be the material 15 of the addition 14, while in Fig. 2, said front wall would be the material of the belt 16. Therefore, the textile material seen in Figs. 3 and 4 at 19 may represent either the element 14 or the element 16 or an equivalent.

To provide an open top for the outer pocket, the material last referred to is slit at 20 and there suitably seamed and stitched as particularly clearly shown in Fig. 4, and to the seams so provided along the upper and lower edges of the slit 20 are stitched to tapes 21 and 22 respectively carrying the cooperating slide fastener elements 23 and 24. Consequently, when the slide fastener 25 is slid from the left, as in Fig. 1, to the right, as in Fig. 3, the outer pocket is closed at its top.

Before the outer pocket is finally completed by adding its bounding lines of stitching 26, the inner pocket, marked generally 27, itself having been previously made, is suspended in the outer pocket 10 by a line of stitching marked 28 in Fig. 4.

The inner pocket 27 is preferably made of two pieces of material, one of which is a back piece 29, folded along its opposite sides to provide plural-ply ribs 30 to be later traversed by the stitching 33. The front piece 31 for the inner pocket is wider than the back piece 29, to provide a fullness sufficient as indicated to comfortably house a plurality of golf balls. With the bottom edge portions of the front and back pieces 29 and 31 stitched together as indicated at 32, the marginal side portions of the front piece 31 are turned in around and behind the ribs 30, and stitched to the latter as indicated at 33; but before this stitching 33 is added, an elastic 34 is extended through a tunnel provided by turning

over and onto the rear side of the front piece 31 the top marginal portion 35 of the front piece 31 and then applying the stitching 36. Whip-stitching is next applied as indicated at 37 to anchor the opposite ends of the elastic 34, with the elastic suitably stretched, to the ribs 30.

The inner pocket 27 is here shown as subdivided, by a line of stitching 38 going through the front and back pieces 29 and 31, for carrying two golf balls each in its own compartment. As will be understood, the inner pocket 27 may be further subdivided, when made of proper length, to accommodate more than two golf balls.

In order to suspend the inner pocket at the outside of the outer pocket 10, when it is desired to have the golf balls in the former quickly removable, the closure for the outer pocket is opened and the inner pocket is lifted out and dropped to hang outside the outer pocket, but then without chance of accidentally losing a golf ball, due to the action of the elastic 34 in holding gathered the upper mouth of the inner pocket.

While I have illustrated and described the preferred embodiments of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In combination with a member having an outer pocket formed of adjacent front and rear walls with the front wall formed with a horizontal elongated pocket opening closed by a slide fastener, an inner pocket for golf balls within the outer pocket, comprising a back piece of material secured along its top edge to the inside face of the front wall of the outer pocket above the pocket opening to depend across the pocket opening within the outer pocket, and a front piece of material secured along its side and bottom edges to the face of said back piece of material adjacent the inner face of the front wall of the outer pocket, said front piece of material being of less height than said back piece of material and secured to said back piece so as to have its top edge normally below the pocket opening of the outer pocket, said inner pocket being of a width less than the length of the pocket opening and secured to the inside face of the front wall of the outer pocket midway of the length of the pocket opening, whereby when the pocket opening is open the inner pocket while containing golf balls may be drawn through the pocket opening to depend along the outer face of the front wall of the outer pocket facilitating insertion and removal of golf balls from the inner pocket.

2. In combination with a member having an outer pocket formed of adjacent front and rear walls with the front wall formed with a horizontal elongated pocket opening closed by a slide fastener, an inner pocket for golf balls within the outer pocket, comprising a back piece of material secured along its top edge to the inside face of the front wall of the outer pocket above the pocket opening to depend across the pocket opening within the outer pocket, and a front piece of material secured along its side and bottom edges to the face of said back piece of material adjacent the inner face of the front wall of the outer pocket, said front piece of material being of less height than said back piece of material and secured to said back piece so as to

have its top edge normally below the pocket opening of the outer pocket, said inner pocket being of a width less than the length of the pocket opening and secured to the inside face of the front wall of the outer pocket midway of the length of the pocket opening, whereby when the pocket opening is open the inner pocket while containing golf balls may be drawn through the pocket opening to depend along the outer face of the front wall of the outer pocket facilitating insertion and removal of golf balls from the inner pocket, and means mounted along the upper edge of said front piece of material for retaining golf balls within the inner pocket.

- 15 3. In combination with a member having an outer pocket formed of adjacent front and rear walls with the front wall formed with a horizontal elongated pocket opening closed by a slide fastener, an inner pocket for golf balls within the outer pocket, comprising a back piece of material secured along its top edge to the inside face of the front wall of the outer pocket above the pocket opening to depend across the pocket opening within the outer pocket, and a front piece of material secured along its side and bottom edges to the face of said back piece of material adjacent the inner face of the front wall of the outer pocket, said front piece of material being of less height than said back piece of material and secured to said back piece so as to have its top edge normally below the pocket opening of the outer pocket, said inner pocket being of a width less than the length of the pocket opening and secured to the inside face of the front wall of the outer pocket midway of the length of the pocket opening, whereby when the pocket opening is open the inner pocket while containing golf balls may be drawn through the pocket opening to depend along the outer face of the front wall of the outer pocket facilitating insertion and removal of golf balls from the inner pocket, said front piece of material having its top edge turned downward and inward and secured to the inside face of the front piece of material forming a tunnel for an elastic, and a piece of elastic extended through said tunnel and having its ends secured to the sides of said inner pocket under tension preventing accidental loss of golf balls from the inner pocket.
- 20 4. In combination with a member having an outer pocket formed of adjacent front and rear walls with the front wall formed with a horizontal elongated pocket opening closed by a slide fastener, an inner pocket for golf balls within the outer pocket, comprising a back piece of material secured along its top edge to the inside face of the front wall of the outer pocket above the pocket opening to depend across the pocket opening within the outer pocket, and a front piece of material secured along its side and bottom edges to the face of said back piece of material adjacent the inner face of the front wall of the outer pocket, said front piece of material being of less height than said back piece of material and secured to said back piece so as to have its top edge normally below the pocket opening of the outer pocket, said inner pocket being of a width less than the length of the pocket opening and secured to the inside face of the front wall of the outer pocket midway of the length of the pocket opening, whereby when the pocket opening is open the inner pocket while containing golf balls may be drawn through the pocket opening to depend along the outer face of the front wall of the outer pocket facilitating inser-

tion and removal of golf balls from the inner pocket, said front piece of material having its top edge turned downward and inward and secured to the inside face of the front piece of material forming a tunnel for an elastic, and a piece of elastic extended through said tunnel and having its ends secured to the sides of said inner pocket under tension preventing accidental loss of golf balls from the inner pocket, and a vertical line of stitches engaged through the pieces of material of the inner pocket midway of the sides thereof from the top edge of the front piece of material to the bottom edges of the pieces of material dividing the inner pocket into adjacent pocket portions for individually receiving golf balls.
